TAP FOR DISPENSING LIQUIDS

Filed Oct. 1 1928

UNITED STATES PATENT OFFICE

JOSEPH HENRY HOLE AND WILFRED ROBERT BRYANT, OF TAUNTON, ENGLAND

TAP FOR DISPENSING LIQUIDS

Application filed October 1, 1928, Serial No. 309,428, and in Great Britain July 18, 1928.

This invention relates to taps for dispensing liquids, and is particularly useful in connection with containers for delivering oils and other valuable liquids. The object of 5 this invention is to provide a form of tap which cannot be left accidentally or intentionally in the delivering position. A further object of our invention is to obviate loss of liquid due to leakage of the tap and to provide a tap which is readily operated.

According to our invention the tap consists of a tubular body adapted to be attached to the desired vessel adaptor or elsewhere, and having its free end engaged by a spring loaded 15 closure member adapted to be moved against the influence of the spring load to open said free end and to also open a discharge outlet in a sleeve slidably disposed about said tubular body.

20 Simple arrangements of levers are adapted to move the spring loaded closure member against the influence of the spring, the said levers being so located and pivoted that a small rocking movement will be sufficient to 25 open the tap and permit the free flow of liquid.

In order that our invention may be readily understood and carried into effect, we append hereto a sheet of drawings illustrating 30 various embodiments and in which,

Fig. 1 is a part sectional elevation of a tap constructed according to our invention.

Fig. 2 is a front end view of Fig. 1.

Fig. 3 is an elevation of a modification 35 showing an alternative arrangement of operating lever.

Fig. 4 is a front end view of Fig. 3.

Fig. 5 shows an arrangement in which the 40 closure spring is arranged outside the body of the tap, this arrangement being particularly useful when used for corrosive liquids.

Fig. 6 is a sectional view taken on line 8-8 of Fig. 5.

45 Referring to Figs. 1 and 2, the tap which may be made of any suitable metal or alloy consists of a tubular body 1 threaded at one end 2 and provided with suitable nuts and washers 3 and 4 for attachment to the appropriate bung hole adaptor or other part of the container &c. to be tapped. The outer end of

the tube 1 is machined externally at 5 to provide a nice cylindrical surface. Fixed to the outer end of this tubular body is a collet 6 between the inner edge 7 of which and the inner edge 8 of a further collet 9 slidable 55 on the tube 1 is a strong coiled compression spring 10.

The slidable collet 9 is fixed inside the inner end of a sleeve 11 concentrically disposed about the said tube and closed at its 60 end by a cap 12 which carries on its inner face a washer 13 composed of a material which will resist the action of the liquid being dispensed and abutting against the machined and if desired bevelled outer edge 14 of the 65 fixed collet 6 thereby under the influence of the said spring sealing the end of the tube.

The slidable sleeve has near its outer end an aperture 15 in its lower side this aperture normally being covered by the fixed collet 6. 70 When it is desired to dispense liquid this aperture is uncovered by sliding the sleeve outwards against the influence of the said spring and this action also moves the cap of the sleeve away from the outer end of the 75 tube with the result that the liquid will flow through the outer end of the tube into the sleeve and out through said aperture.

The opening movement of the sleeve can be effected by a lever 16 in the form of two 80 symmetrical arms 16a pivoted at one end to a common bracket 17 and fulcrumed on a common axis 18 to the slidable collet, the other ends of the arms being bridged by a horizontal handle 19. To open the tap the operator places the palm of a hand against the cap at the front end of the sleeve and engages the said handle with the fingers. A gripping action will now compress the spring 85 and open the said aperture. The tap is closed 90 by merely releasing the handle.

The bracket to which the lever is connected can be a ring secured by a nut 20 or otherwise about the threaded part of the tube and having a depending L shaped lug 21 to receive the two arms constituting said lever. 95

In another arrangement shown in Figs. 3 and 4, each of said arms can be L shaped, as at 22, the corner of each arm being fulcrumed at 23 to the sliding sleeve 11 and the outer end 100

of the shorter limb 24 of each arm being pivoted to said L shaped lug of the said bracket. The free ends of the other limbs 25 extend slightly beyond said cap 12 and are bridged by a handle 19 which is also adapted to be engaged by the finger of a hand for opening the tap, the thumb of the hand being pressed against a thumb rest 26 extending horizontally beyond and attached to said cap.

A further modification is illustrated in Figs. 5 and 6 showing a construction which is particularly useful for corrosive fluids and in this arrangement the spring 10 is shown to be out of contact with the liquid and surrounding the outer circumference of the sleeve 11 being interposed between a collet 39, secured to the said sleeve and a collet 40 which is a sliding fit on sleeve 11 and secured by two diametrically opposite rods 41 attached to the bracket 17. The rods 41 pass through lugs 42 on the collet 39, these lugs also serving as pivots for the levers 16. It will be seen that by placing the palm of the hand upon the cap 12 and grasping the lever 16 between the fingers that the sleeve 11 with its collet 39 may be moved to overcome the pressure of the spring 10 and allow the opening of the outlet aperture.

What we claim is:—

1. In a tap of the type described a washer faced sleeve like body slidable on and adapted to abut against the outlet end of a tube adapted to be inserted at its other end into a liquid container or a source of liquid supply, the washer normally sealing such outlet end of the tube and being mounted in one end of said sleeve like body, a coiled compression spring arranged between abutments carried by the tube and sleeve and normally pressing said washer upon the outlet end of the tube, and a hand lever pivotally connected to the sleeve and to the tube for moving said washer from the outlet end of said tube, the said outlet end of the said tube delivering into said sleeve like body, and an escape port in the side of said sleeve like body normally closed by the side of the outer end portion of said tube.

2. In a tap of the type described a washer faced sleeve like body slidable on and adapted to abut against the outlet end of a tube adapted to be inserted at its other end into a liquid container or a source of liquid supply, the washer normally sealing such outlet end of the tube and being mounted in one end of said sleeve like body, a coiled compression spring arranged between abutments carried by the tube and sleeve and normally pressing said washer upon the outlet end of the tube, and a hand lever pivotally connected to the sleeve and to the tube for moving said washer from the outlet end of said tube, the said outlet end of the said tube delivering into said sleeve like body, and an escape port

in the side of said sleeve like body normally closed by the side of the outer end portion of said tube, said spring being arranged inside the said sleeve like body between it and the tube, the pressure of the spring being adapted to be overcome by rocking said lever which is pivoted to a bracket forming a fixed part of the tap.

3. In a tap of the type described a washer faced sleeve like body slidable on and adapted to abut against the outlet end of a tube adapted to be inserted at its other end into a liquid container or a source of liquid supply, the washer normally sealing such outlet end of the tube and being mounted in one end of said sleeve like body, a coiled compression spring arranged between abutments carried by the tube and sleeve and normally pressing said washer upon the outlet end of the tube, and a hand lever pivotally connected to the sleeve and to the tube for moving said washer from the outlet end of said tube, the said outlet end of the said tube delivering into said sleeve like body, and an escape port in the side of said sleeve like body normally closed by the side of the outer end portion of said tube, said spring being arranged inside the said sleeve like body between it and the tube, the pressure of the spring being adapted to be overcome by rocking said lever which is pivoted to a bracket forming a fixed part of the tap, the lever being of L shape and pivoted between its ends at its corner to a bracket secured as a fixed part of the tap and adapted to be actuated by raising the longer limb to move said sleeve against the spring load.

4. In a tap of the type described, a washer faced sleeve like body slidable on and adapted to abut against the outlet end of a tube adapted to be inserted at its other end into a liquid container or a source of liquid supply, the washer normally sealing such outlet end of the tube and being mounted in one end of said sleeve like body, a coiled compression spring arranged between abutments carried by the tube and sleeve and normally pressing said washer upon the outlet end of the tube, and a hand lever pivotally connected to the sleeve and to the tube for moving said washer from the outlet end of said tube, the said outlet end of the said tube delivering into said sleeve like body, and an escape port in the side of said sleeve like body normally closed by the side of the outer end portion of said tube, said spring being arranged inside the said sleeve like body between it and the tube, the pressure of the spring being adapted to be overcome by rocking said lever which is pivoted to a bracket forming a fixed part of the tap, the lever being of L shape and pivoted between its ends at its corner to a bracket secured as a fixed part of the tap and adapted to be actuated by raising the longer limb to move said sleeve against the spring load, and a thumb

piece co-operating with said lever and secured to the cap of the closure member.

5. In a tap of the type described a washer faced sleeve like body slideable on and adapted to abut against the outlet end of a tube adapted to be inserted at its other end into a liquid container or a source of liquid supply, the washer normally sealing such outlet end of the tube and being mounted in one end of said sleeve like body, a coiled compression spring arranged between abutments carried by the tube and sleeve and normally pressing said washer upon the outlet end of the tube, and a hand lever pivotally connected to the sleeve and to the tube for moving said washer from the outlet end of said tube, the said outlet end of the said tube delivering into said sleeve like body, and an escape port in the side of said sleeve like body normally closed by the side of the outer end portion of said tube, said spring being arranged around the outer circumference of said sleeve abutting at its outer end against a collet secured by longitudinal rods to a bracket forming a fixed part of the tap and at its other end against a collet forming part of said sleeve.

In witness hereof we have signed this specification.
